ASH TRAY

Walter R. Orell, South St., Blandford, Mass. 01008
Filed Jan. 9, 1967, Ser. No. 5,340

Term of patent 14 years

(Cl. D85—2)

FIG. 1 is a top perspective view of an ash tray showing my new design;

FIG. 2 is a top plan view;

FIG. 3 is an end elevational view;

FIG. 4 is a side elevational view;

FIG. 5 is a top perspective view of an ash tray showing my new design wherein a modified form of cigarette rest is utilized; and

FIG. 6 is a top perspective view of an ash tray showing my new design wherein a modified wall form is utilized.

I claim:

The ornamental design for ash tray, as shown and described.
